UNITED STATES PATENT OFFICE

2,424,555

CUTTING APPARATUS

Dale M. Curtis, Nitro, W. Va., assignor to American Viscose Corporation, Wilmington, Del., a corporation of Delaware

Application July 10, 1945, Serial No. 604,143

11 Claims. (Cl. 164—38)

1

The present invention relates to apparatus for cutting continuous filamentary material into discontinuous lengths for the production of staple fiber from rayon or other synthetic filamentary material. The invention is particularly concerned with that type of fiber-cutting apparatus in which the continuous material is fed to a rotating member having a radial channel through which the material is directed outwardly, generally under the influence of centrifugal force and from which the material protrudes until cut by a cutting member which co-operates with the periphery of the rotating member. The general form of the cutting apparatus is shown in Beria Patent No. 1,723,998.

Occasionally, the fibers protruding from the rotating member are not completely severed, either because of dullness of the knife or equivalent cutting member, or because of improper co-action of the knife or filament cutting member with the rotating member. When this occurs, the fiber product will contain a certain proportion of overlength fibers which may be two or three times as long as the fiber length desired. In accordance with the present invention, overlength fibers are detected and such detection initiates the operation of means for interrupting the cutting and indicating the interruption. In this fashion, the operator is advised immediately of the improper functioning of the cutting apparatus. Another object of this invention is to provide means for preventing loss of tension in the material even after interruption of cutting. Further objects and advantages of the invention will be apparent from the drawing and the description herein.

The drawing illustrates preferred embodiments of the invention, the electrical connections being somewhat schematically shown.

Figure 1 is a perspective view of one form of the invention, and

Figure 2 is a perspective view of a modification.

The cutting apparatus as shown in Figure 1 comprises a rotating member 2 which may be termed a rotating disc or cutting head. The rotating member 2 is provided with a radial channel 3 which communicates with the axial feeding and guiding member 4 into which the filamentary material 5 may be fed downwardly by means of a delivery roll or godet 6 (or any equivalent feeding device such as a thread-advancing device comprising a pair of canted rolls, a thread-advancing reel, or the like) about which the material 5 is lapped one or more times to provide a good grip. The delivery roll 6 is driven by a shaft 7 and conventional driving means, not shown. A

2

knife 8 is carried by a suitable bracket 9 fastened to a supporting frame 10, so that the protruding fiber clump 5a is cut each time the rotating member 2 carries it into contact with the knife 8.

5 The rotating member 2 may be supported in suitable bearings upon the support 11 and may be driven by pulley 12 therebeneath.

One or more (two being shown) detecting fingers 13 are positioned radially outwardly from the periphery of the rotating member 2. Suitably, each finger 13 may be carried upon a transverse rod or shaft 14 pivotally mounted in a bracket 15 secured to the framework 10. There is also secured to the rod 14 a mercury switch 16.

15 The pivotal assemblage of finger 13, rod 14 and switch 16 are so balanced that the finger 13 extends downwardly and is positioned just outside the normal path of the protruding fibers 5a. Since the amount by which the fiber clump 5a ex-

20 tends outwardly from the rotating member 2 depends upon the arcuate distance of the clump from the cutting member 8 at any particular portion of the path, the first detector finger 13 which the fiber clump 5a approaches after leav-

25 ing the position of the cutting member 8 is positioned a much shorter radial distance from the periphery of the member 2 than the subsequent detector finger or fingers 13. However, each one is positioned just outside the normal path of the

30 fiber clump, so that when the cutting apparatus is operating properly, there is no contact between the fiber clump 5a and the detector fingers 13. The mercury switches 16 are normally open when the apparatus is functioning properly.

35 However, when overlength fibers occur in the clump 5a, such fibers strike the detector finger or fingers 13, and cause pivotal motion thereof about the axis of rod 14, thereby swinging the mercury switch and closing its contacts. A hooked guide

40 17 is shown adjacent the path taken by the continuous filamentary material from the delivery roll 6 to the mouth 4 of the rotating member 2. A spring 18 within the housing 19 has its outermost end secured to the shank of the guide 17 and

45 normally holds the guide 17 in the position shown. A solenoid 20 is arranged to cause the guide 17 to move transversely of the path of the material 5, thereby forcing it out of its normal path to the cutter and interrupting cutting. The solenoid 20

50 is operated whenever one of the switches 16 is closed. A signal light 21 and a sound alarm 22 may be connected in the circuit so that the closing of switches 16 or any one of them also sounds the alarm and turns on the light to call the operator's attention to the improper functioning of

the machine. An electric supply line 23 may be connected to the electrical control system by the master switch 24 during operation of the cutting apparatus.

The electrical controlling system so far described is essentially complete in itself. However, an auxiliary detector system may be provided to indicate any decrease in tension of the material proceeding from the delivery roll 6 to the cutting head 2. This detector may take the form of a feeler 25 normally pressing against the material 5 as it proceeds between roll 6 and cutter head 2 and mounted upon a shaft 26 pivotally supported within a bracket 27 and carrying a mercury switch 28 which is normally open in the position shown when the filamentary material 5 is feeding properly. When failure of the material 5 occurs because of breakage, or whenever a decrease in tension occurs for any reason, the detector system 25, 26 and 28 swings pivotally in the direction shown by the arrow, thereby closing the mercury switch 28, sounding the alarm 22 and lighting the light 21. An auxiliary stationary guide 29 may be provided in the bracket 27 to reduce fluctuation and vibration in the material 5 as it passes between the roll 6 and the cutter head 2.

In Figure 2, the arrangement of Figure 1, is modified by the provision of means for withdrawing the material from the vicinity of the cutter. This means may illustratively comprise a conduit 30 discharging into a container 31 (or to any other device for receiving the material either in heaped or wound form), and an injector 32 for inducing suction at the entrance 33 to the conduit. The mouth or entrance 33 is positioned so that when the material is deflected from its normal path to the cutter by hook 17, it is presented to the entrance 33 and is sucked into it. A solenoid-controlled valve 34, normally held closed by a spring in conventional fashion, permits air or other high pressure fluid available in line 35 to enter the injector 32 by line 36.

Whenever the material breaks, suffers a loss in tension, or is deflected by hook 17 in response to overlength fibers, the valve 34 opens and operates injector 32, thereby sucking the material into the conduit 30, discharging it from the scene of cutting operation, and maintaining tension in the material being fed around the roll 6 or equivalent thread-feeding or thread-advancing device. This is important when the filamentary material comprises an aggregate of individual bundles or filaments coming from a plurality of sources by converging routes, such as from the spinnerets of a spinning machine, since without the maintenance of tension after interruption of cutting, it is in this case necessary to lace up the entire machine anew.

While mercury switches 16 and 28 are disclosed, any other type of switch may be used. For example, the swinging of the detector systems may move a metallic contact into engagement with a stationary metallic contact in order to effect closing of the electrical control system.

The present invention provides for independent detection and signaling (1) of breakage or failure of tension in the filamentary material as it proceeds from the roll 6 to the cutter 2 and (2) of the improper functioning of the cutting member 8 resulting in overlength fibers. In the latter event, the detector system initiates operation of means for interrupting the cutting action, means for notifying operators and, in the embodiment of Figure 2, means for maintaining

4 a predetermined minimum tension in the material proceeding from the delivery roll.

It is to be understood that the description hereinabove is illustrative only, and that changes and variations may be made without departing from the spirit and scope of the invention as defined in the appended claims.

I claim:

1. In combination, means for cutting continuous filaments into discontinuous lengths, means for delivering the material to the cutting means, means for interrupting delivery of the material to the cutting means, and means operated upon interruption of such delivery for maintaining a predetermined minimum tension in the material proceeding from the delivery means.

2. In combination, means for cutting continuous filaments into discontinuous lengths, means for delivering the material to the cutting means, means for interrupting delivery of the material to the cutting means, detector means responsive to decrease in tension, to breakage, and to improper cutting for initiating operation of the delivery interrupting means, and means operated upon interruption of such delivery for maintaining a predetermined minimum tension in the material proceeding from the delivering means.

3. In apparatus for cutting continuous filamentary material to discontinuous lengths, cutting means, means for delivering the material to the cutting means, means for interrupting delivery of the material to the cutting means, means for maintaining a predetermined minimum tension in the material proceeding from the delivery means during periods of interrupted delivery to the cutting means and detector means responsive to improper functioning of the apparatus for initiating operation of the delivery interrupting means.

4. In combination with a device for cutting continuous filaments into discontinuous lengths comprising a rotating member having a radial passage for discharging the filamentary material outwardly therefrom, a cutting member to which the rotating member presents the outwardly extending material to be cut, and means for delivering continuous filamentary material to the rotating member; means for interrupting cutting, and means positioned a predetermined distance radially from the rotating member for detecting filament ends of excessive length extending outwardly therefrom and for initiating operation of the interrupting means in response to such detection.

5. In combination with a device for cutting continuous filaments into discontinuous lengths comprising a rotating member having a radial passage for discharging the filamentary material outwardly therefrom, a cutting member to which the rotating member presents the outwardly extending material to be cut, and means for delivering continuous filamentary material to the rotating member; means for interrupting delivery of the material to the rotating member, and means positioned a predetermined distance radially from the rotating member for detecting filament ends of excessive length extending outwardly therefrom and for initiating operation of the interrupting means in response to such detection.

6. In combination with a device for cutting continuous filaments into discontinuous lengths comprising a rotating member having a radial passage for discharging the filamentary material outwardly therefrom, a cutting member to which

the rotating member presents the outwardly extending material to be cut, and means for delivering continuous filamentary material to the passage in the rotating member; a movable element positioned along the path of the material on its way to the rotating member, means for moving the element across the path thereby deflecting the material therefrom, and means positioned a predetermined distance radially from the rotating member for detecting filament ends of excessive length extending outwardly therefrom and for initiating operation of the moving means.

7. In combination with a device for cutting continuous filaments into discontinuous lengths comprising a rotating member having a radial passage for discharging the filamentary material outwardly therefrom, a cutting member to which the rotating member presents the outwardly extending material to be cut, and means for delivering continuous filamentary material to the passage in the rotating member; a movable element positioned along the path of the material on its way to the rotating member, means for moving the element across the path thereby deflecting the material therefrom and withdrawing it from the passage in the cutting member, and means positioned a predetermined distance radially from the rotating member for detecting filament ends of excessive length extending outwardly therefrom and for initiating operation of the moving means.

8. In combination with a device for cutting continuous filaments into discontinuous lengths comprising a rotating member having a radial passage for discharging the filamentary material outwardly therefrom, a cutting member to which the rotating member presents the outwardly extending material to be cut, and means for delivering continuous filamentary material to the rotating member; a moving element positioned along the path of the material on its way to the rotating member, electrical means for moving the element across the path thereby deflecting the material therefrom and withdrawing it from the passage in the cutting member, and switch means positioned a predetermined distance radially from the rotating member for detecting filament ends of excessive length extending outwardly therefrom and for initiating operation of the electrical moving means.

9. In combination with a device for cutting continuous filaments into discontinuous lengths comprising a rotating member having a radial passage for discharging the filamentary material outwardly therefrom, a cutting member to which the rotating member presents the outwardly extending material to be cut, and means for delivering continuous filamentary material to the rotating member; a movable element positioned along the path of the material on its way to the

rotating member, electrical means for moving the element across the path, thereby deflecting the material therefrom and withdrawing it from the passage in the cutting member, and pivotally mounted switch means positioned a predetermined distance radially from the rotating member for detecting filament ends of excessive length extending outwardly therefrom, said switch means being swingable to a closed position on receiving an impact from the filament ends of excessive length for initiating operation of the electrical moving means.

10. In combination with a device for cutting continuous filaments into discontinuous lengths comprising a rotating member having a radial passage for discharging the filamentary material outwardly therefrom, a cutting member to which the rotating member presents the outwardly extending material to be cut, and means for delivering continuous filamentary material to the rotating member; a moving element positioned along the path of the material on its way to the rotating member, electrical means for moving the element across the path thereby deflecting the material therefrom and withdrawing it from the passage in the cutting member, switch means positioned a predetermined distance radially from the rotating member for detecting filament ends of excessive length extending outwardly therefrom and for initiating operation of the electrical moving means, a pivotally mounted member arranged to engage the material on its way to the rotating member, switch means carried by the pivotally mounted member, said switch being normally open during normal cutting operation but being closed upon tilting motion of the pivotally mounted member in response to decrease in tension of the material, and signal means operated upon closing of the switch.

11. In apparatus for cutting filamentary material to discontinuous lengths, cutting means, material delivery means, means beyond the delivery means for guiding the material discharged from the delivery means to the cutting means, means between the delivery means and the guiding means for withdrawing the filamentary material from the guiding means, and detector means responsive to improper functioning of the apparatus for initiating operation of the withdrawing means.
